(57) CLAIM

The ornamental design for a cosmetic box, as shown and described.

DESCRIPTION

FIG. 1 is a perspective view of a first embodiment of a cosmetic box showing the new design, the cosmetic box shown in a closed state;

FIG. 2 is a perspective view of the cosmetic box of FIG. 1, shown in an open state;

FIG. 3 is a front view thereof;

FIG. 4 is a back view thereof;

FIG. 5 is a side view thereof;

FIG. 6 is another side view thereof;

FIG. 7 is a top view thereof;

FIG. 8 is a bottom view thereof; and,

FIG. 9 is a front view of a second embodiment of the cosmetic box showing the new design, with the back, top, bottom and side views being identical to the first embodiment.
